UNITED STATES PATENT OFFICE

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN

INTERNAL-COMBUSTION ENGINE

Application filed February 23, 1924. Serial No. 694,574.

This invention relates to internal combustion engines and particularly to the cylinder, crankcase, crankshaft, bearings and related parts.

5 One of the objects of the present invention is to provide a strong and light weight engine.

Another object of the invention is to provide a barrel crankcase with integral cylinder parts.

Another object of the invention is to provide a barrel crankcase engine with adequate end thrust means for the crankshaft.

Another object of the invention is to provide for ready removal of the crankshaft from a crankcase of barrel form.

Another object of the invention is to provide an extremely light weight engine with adequate means for supporting the crankshaft for high speed operation.

Another object of the invention is to provide a crankshaft bearing member with a novel form of positioning and clamping means in the crankcase of an engine.

25 Other objects of the invention will appear from the following description taken in connection with the drawings, which form a part of this specification, and in which:

Fig. 1 is a longitudinal section through an 30 engine embodying the invention;

Fig. 2 is a vertical transverse section substantially on the line 2—2 of Fig. 1, and

Fig. 3 is an enlarged section on the line 3—3 of Fig. 2.

35 Referring to the drawing, 10 represents the crankcase casting generally. This crankcase casting is of barrel form in that it extends the full length of the engine and it entirely surrounds the crankshaft. The 40 upper part of the casting has an integral upward extension which forms a portion of the engine cylinder block. As shown, this upward extension, which is indicated at 11, forms the outer wall of the jacket of the

45 cylinder block and the inner wall of the jacket is formed by the several cylinders 12 which extend down into the portion 11 and are secured in place by a detachable head 13. The head is bolted to the main casting by a series 50 of bolts 14 shown particularly in Fig. 2.

The lower wall of the crankcase into which the oil drains is indicated at 15, this wall being an integral part of the crankcase casting 10, and the side walls of the crankcase are provided with rather large openings 16, 55 one on each side, for insertion and removal of the connecting rods. These openings 16 are closed by covers 17 detachably secured by bolts and nuts 18.

The engine pistons are indicated at 19 and the connecting rods at 20. 21 is the crankshaft of the engine. The engine illustrated is a six-cylinder engine so that there are six throws to the crankshaft and there are six pistons and six connecting rods. Also, the 60 engine shown has a three-bearing crankshaft, the two end bearings and a single intermediate bearing, and the crankcase is accordingly made to provide for these three bearings.

70 Referring particularly to Fig. 1, one of the end bearings is indicated at 22 and the other end bearing at 23. These are ball bearings of sufficient size to take the crankshaft load. In the claims these bearings will be 75 referred to as anti-friction bearings to distinguish from the usual plain bearings used in internal combustion engines. The bearing 22 is supported in a sleeve 24 mounted in the end wall 25 of the crankcase. This 80 bearing is withdrawable from the sleeve 24 with the crankshaft as will hereinafter appear.

The bearing 23 is supported in a ring or sleeve 26 which is mounted in the other end wall 27 of the crankcase 10 and this ring 26 is detachably held in place by a series of bolts 28. The opening 29 into which the ring 26 fits is slightly larger in diameter than the greatest diameter of the crankshaft 21 so that the crankshaft may be inserted into and removed from the crankcase through this opening.

85 The intermediate or middle bearing part 30 of the crankshaft 21 is supported in a 90 bearing member 31 in an intermediate transverse wall 32 of the crankcase casting 10. This bearing member is formed in two parts bolted together as by bolts 31', shown in Fig. 2, and it is preferably babbitted as at 33 to 100

provide a suitable bearing surface for the crankshaft. In the claims this bearing will be referred to as a plain bearing. The babbitt extends at the sides of the member 31 as shown at 34 and thereby contacts with the cheeks 35 of the crankshaft and takes the end thrust of the crankshaft or positions the crankshaft endwise in the crankcase.

Oil is fed to the bearing 30 from a pipe 36 through a passage 37 in the wall 32 of the crankcase and through a passage 38 in the lower part of the bearing element 31, the passage 38 leading directly to the bearing surface of the babbitt lining 33. The exterior of the bearing element 31 is cylindrical and it fits in an opening 39 in the wall 32, which opening is slightly larger than the greatest diameter of the crankshaft so that the latter may be removed through the opening 39, together with the bearing member 31, when the latter is disconnected. The bearing member 31 is positioned in the crankcase by a pair of bolts or dowels 40 which are shown particularly in Figs. 2 and 3. It is secured in place by a pair of bolts 41 which extend through bosses 42 formed in the wall 15 of the crankcase and threaded into the bearing member 31 as shown at 43 in Fig. 2. The bolts 41 are arranged one on each side of the aligned passages 37, 38 and by drawing the bearing member 31 downwardly in close contact with the lower wall of the opening 39, a tight joint is made so that there will be no leakage of oil at that point.

In assembling the crankshaft in the crankcase it will be understood that the bearings 22 and 23 will be placed on the ends of the crankshaft, the ring 26 will be placed over the bearing 23, and the bearing member 31 will be clamped around the intermediate bearing part 30 of the crankshaft. The bolts or dowels 40 will be backed out of the way and the bolts 41 will be out. The crankshaft will then be inserted endwise through the openings 29 and 39 of the crankcase and the bearing 22 will rest in the sleeve 24, the bearing member 31 will rest in the wall 32, and the ring 26 will rest in the end wall 27. The member 31 will then be positioned by threading in the bolts 40 and it will then be clamped in place by inserting the bolts 41. The ring 26 will be bolted to the crankcase by the bolts 28. The pistons 19 and connecting rods 20 may then be assembled through one or the other of the side openings 16 and the latter will be closed by the covers 17.

The bottom wall 15 is preferably formed with openings 44 at or near its lowest point so that the oil therein may drain into a reservoir 45, which is detachably secured to the lower part of the crankcase as by bolts 46. A suitable pump, not shown, may be provided to draw oil from the reservoir 45 and feed it to the pipe 36. A relief valve is in-

dicated at 47 in Fig. 2, having a pipe 48 connecting it with the pipe 36 and having an overflow passage 49 back into the reservoir 45.

A carburetor is indicated at 50 and an intake pipe at 51 and a throttle valve 52 is operated by suitable connections 53.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the spirit or scope of my invention.

Having thus described my invention, what I claim and desire to secure by Letters Patent is:

1. In an internal combustion engine, the combination with a multithrow crankshaft of a barrel crankcase having side openings and an end opening large enough to receive the crankshaft, said side openings being large enough for insertion and removal of the connecting rods, the crankcase being adapted to have the crankshaft assembled through said end opening and three bearings in said crankcase for said crankshaft.

2. In an internal combustion engine, the combination of a crankcase having anti-friction end bearings and a plain intermediate main bearing and a crankshaft mounted in said bearings, said intermediate bearing being arranged to take all of the end thrust of the crankshaft and the anti-friction bearings being longitudinally movable in said crankcase.

3. In an internal combustion engine, the combination with a crankcase and an endwise removable crankshaft therein, of an intermediate bearing for said crankshaft, a bearing disk secured around said bearing, anchored in the crankcase and adapted with the bearing to take the end thrust of the crankshaft.

4. In an internal combustion engine, the combination of a barrel crankcase, end bearings therein for the crankshaft, an intermediate split bearing comprising two pieces adapted to surround an intermediate bearing part of the crankshaft, means cooperating with one of said pieces for positioning said intermediate bearing in the crankcase, means cooperating with said other piece to clamp said intermediate bearing in said crankcase and a crankshaft supported in said bearings.

5. In an internal combustion engine, the combination with the crankcase having an opening therein for endwise removal of the crankshaft, a bearing member arranged in said opening, said crankcase and bearing member having aligned oil passages, and

means for clamping the bearing member to the crankcase adjacent said oil passage.

6. In an internal combustion engine, the combination with the crankcase having an opening therein for endwise removal of the crankshaft, a bearing member arranged in said opening, said crankcase and bearing member having aligned oil passages, means for positioning said bearing member in the crankcase opening, and means for clamping the bearing member to the crankcase so that a tight joint will be made where the oil passages meet.

In testimony whereof I affix my signature.

15 JESSE G. VINCENT.
